ATTORNEY'S

UNITED STATES PATENT OFFICE

EVERETT J. COOK, OF TOLEDO, OHIO, ASSIGNOR TO THE DURA COMPANY, OF TOLEDO, OHIO, A CORPORATION OF OHIO

DOORLATCH

Application filed December 22, 1930. Serial No. 504,103.

The invention relates to door latches and refers more particularly to door latches for motor vehicles. One of the objects of the invention is to provide a door latch so constructed that a party may, if desired, lock himself within the motor vehicle, but he cannot accidentally lock himself out of the motor vehicle. Another object is to provide a door latch with control means operable from inside the door to render the outside door handle ineffective and with means operable upon closing the door to render the control means ineffective. These and other objects of the invention will be apparent from the following description, taken in connection with the accompanying drawings, in which

Figure 1 is a side elevation of a door latch, showing an embodiment of my invention with the latch bolt in latching position and the other parts in non-dogging position;

Figure 2 is a corresponding view with the latch bolt in latching position and the other parts in dogging position;

Figure 3 is a corresponding view with the latch bolt in releasing position and the other parts in dogging position;

Figure 4 is a plan view thereof;

Figure 5 is a perspective view thereof, partly broken away;

Figure 6 is a cross sectional view taken on the line 6—6 of Figure 2;

Figure 7 is a cross sectional view taken on the line 7—7 of Figure 2;

Figure 8 is a side elevation of the keeper.

The door latch illustrated in the present instance is applicable to a vehicle and more particularly a closed motor vehicle. This door latch has the case plate 1, which is secured to the door, the cover plate 2, the latch bolt 3, the keeper 4, which is secured to the door frame, and mechanism for actuating the latch bolt from both inside and outside the door.

The case plate has the body 5 and the transverse flange 6, which latter is apertured for the passage of the latch bolt. The cover plate extends substantially parallel to the body 5 and is secured in spaced rela-

tion thereto by the tongue 7, which is struck out from the body and has a reduced end portion riveted over the cover plate, and by the tongue 8 which extends from and is shorter than the cover plate, this tongue 55 passing through the flange 6 and being riveted thereover at its ends. The latch bolt is pivotally mounted between the case and the cover plates, it being journalled upon the bushing 9, which in turn extends through 60 the case and cover plates and is journalled therein. The keeper has the shoulder 10 engageable with the latch bolt to hold the door closed and the cam face 11 engageable with the latch bolt upon swinging the latter upwardly from its latching position to its releasing position to cam the latch bolt outwardly and thereby initially open the door. This cam face also compels the latch bolt to swing downwardly from its releasing position to its latching position upon closing the door.

For holding the latch bolt in either its latching position or its releasing position, there is the off-center functioning device 12, 75 which comprises the plunger bars 13 and 14 overlapping and slidably engaging each other and the coil spring 15 encircling these plunger bars and abutting their heads. One plunger bar fulcrums on the tongue 16 struck out from 80 the case plate body 5 and the other plunger bar fulcrums on the extension 17 formed integrally with the latch bolt and extending rearwardly from the bushing. The arrangement is such that during the swinging of the 85 latch bolt in either direction it is forcibly urged by the device as soon as the fulcrum point for the device upon the extension of the latch bolt is out of the line connecting the fulcrum point upon the tongue for the device 90 and the pivotal axis of the latch bolt.

18 is the outside door handle having its spindle fitting in the polygonal recess 19 extending longitudinally within the bushing 9. 20 is the inside door handle disposed in the 95 present instance at a point remote from the door latch. This handle is mounted upon and secured to the shaft 21 which is journalled in the case and cover plates 22 and 23 respectively of the remote control mechanism 100.

mounted upon the door. 24 is the crank arm secured upon the shaft 21 and pivotally connected at its free end to the rear end of the link 25. 26 is the spring engageable with 5 opposite sides of the peripheral projection 27 upon the segmental portion of the crank arm to resiliently hold the crank arm in different positions of rotative adjustment. 28 is the coil spring having one end anchored to the 10 case plate 22 and the other end anchored to the crank arm 24 and resiliently urging the crank arm in a direction to move the link 25 forwardly. The transverse end 29 of the coil spring for anchoring this spring to the crank 15 arm extends through the arcuate slot 30 of the crank arm and is engageable with the shoulders 31 and 32 formed upon the cover plate 23 to limit the swinging movement of the inside door handle.

20 33 is the lever journaled upon the bushing 9 between the latch bolt 3 and the case plate body 5 and having the transverse projection 34 extending over the latch bolt and engageable with the extension 17 of the latch bolt to 25 swing the latch bolt from its latching position to its releasing position. This lever has at its free end the slot 35 through which extends the shouldered pin 36 upon the front end of the link 25. 37 is the 30 lever fixedly secured upon the bushing 9 beyond the cover plate 2 and having the transverse projection 38 which passes over the edge of the cover plate and also over the projection 35 of the lever 33. The projection 38 35 has the inturned flange 39 which is engageable with the adjacent edge of the projection 34 so that upon rotation of the outside handle 18 the lever 37 through the lever 33 moves the latch bolt 3 from its latching position to 40 its releasing position.

For the purpose of rendering the outside door handle 18 ineffective, there is the pawl 40 which is pivotally mounted at its lower end upon the cover plate 2, which has the transverse flange 41 at its upper end located between the shouldered pin 36 and the case plate flange 6 and engageable with the shouldered pin and which has the shoulder 42 intermediate its ends and positioned to engage the 50 projection 38 of the lever 37 when the pawl is swung toward the case plate flange 6. The coil spring 28 acting through the crank arm 24 and the link 25 normally hold the lever 33 and consequently the lever 37 in positions 55 such that the projection 38 of the lever 37 will clear the shoulder 42 of the pawl 40 when the latter is swung into dogging position. By swinging the inside door handle 20 in the bolt non-retracting direction to engage the spring 60 26 with the opposite side of the peripheral projection 27, the shouldered pin 36 is brought into engagement with the transverse flange 41 upon the pawl 40 and this pawl is swung to dogging position, at which time this shoulder 42 engages behind the projection 38 of

the lever 37. At this time the outside door handle is held from rotation and cannot be used to retract the latch bolt, so that unauthorized entry into the motor vehicle cannot be accomplished through the outside door handle. 70

To prevent the possibility of a party being accidentally locked out of the motor vehicle, if the inside door handle were accidentally swung in a bolt non-retracting direction and if the door were closed, the pawl 40 is formed with the transverse arcuate flange 43 between its pivot and its shoulder 42 and so located that upon movement of the latch bolt 3 from its releasing to its latching positions its extension 17 contacts with this arcuate flange and compels the pawl to swing to its inoperative position, at which time its shoulder clears the projection 38 upon the lever 37. At this time the crank arm is compelled to swing to a position where the spring 26 engages the opposite side of the peripheral projection 27. 80

44 is a suitable spring looped around the pivot for the pawl 40 and having one end engaging the pawl and the other end engaging the tongue 45 extending transversely from the cover plate 2, this spring functioning to normally hold the pawl in its inoperative position. The tongue 45 is engageable with the lower end of the pawl to limit its movement 95 under the action of the spring 44.

From the above description, it will be seen that the door latch illustrating an embodiment of my invention may be operated by a party within the motor vehicle to render the 100 outside door handle ineffective in opening the door. It will also be seen that the door latch is so constructed that a party cannot accidentally lock himself out of the motor vehicle since the closing of the door automatically renders the outside door handle operative. 105

What I claim as my invention is:

1. In a door latch, the combination with a 110 latch bolt, of levers at opposite sides of said latch bolt for actuating the same, a member engageable with one of said levers to hold the same from actuating said latch bolt, and means for actuating the other of said levers and controlling the engagement of said holding member and the first mentioned of said levers. 115

2. In a door latch, the combination with inside and outside door handles and a latch bolt, of a lever connected to said outside door handle and adapted to actuate said latch bolt, a second lever connected to said inside door handle and adapted to actuate said latch bolt, a member engageable with said first mentioned lever to hold the same from actuating said latch bolt, means dependent upon movement of said inside door handle for moving said member into engagement with said first mentioned lever, and cooperating means upon said latch bolt and member for returning 120 125 130

- said member upon movement of said latch bolt in one direction.
3. In a door latch, the combination with an outside door handle, case and cover plates, and a pivotal latch bolt between said plates, of a pivotal lever between said latch bolt and case plate and adapted to swing said latch bolt from its latching position to its releasing position, a second pivotal lever at one side of said cover plate and adapted to engage said first mentioned lever to swing said latch bolt from its latching position to its releasing position, said second mentioned lever being connected to said outside handle, a pawl pivotally mounted upon said cover plate and provided with a shoulder engageable with said second mentioned lever to dog the same, means at the inside of the door for moving said pawl to dogging position, and cooperating means upon said pawl and latch bolt for moving said pawl from dogging position upon swinging of said latch bolt from releasing position to latching position. 70
4. In a door latch, a case plate having a tongue, a latch bolt on the case plate and having an extension, and means for moving the bolt from latching to releasing positions including overlapping plunger bars having heads respectively fulcrumed on the tongue and extension, and a coil spring sleeved upon said bars between said heads. 80
5. In a door latch, a case plate, a cover plate on the case plate, a bushing carried by said plates, a latch bolt journaled upon the bushing and having an extension, and a lever journaled on the bushing and having a projection engageable with the bolt extension to move the bolt from its latching to its releasing positions. 90
6. In a door latch, a case plate, a cover plate on the case plate, a bushing carried by said plates, a latch bolt journaled upon the bushing and having an extension, a lever journaled on the bushing and having a projection engageable with the bolt extension to move the bolt, and a lever fixedly secured upon the bushing and having a projection engageable with the projection of the lever aforesaid to cause the bolt to move. 100
7. In a door latch, a case plate, a cover plate on the case plate, a bushing carried by said plates, a latch bolt journaled upon the bushing and having an extension, and actuating means for the bolt including a lever journaled on the bushing and having a projection engageable with the bolt extension, a second lever fixedly secured upon the bushing and having a projection engageable with the projection aforesaid, and a handle having a spindle non-rotatably secured to the bushing so that movement of the handle will cause the two levers aforesaid to move the bolt. 110
8. In a door latch, a latch bolt having an extension, actuating means for the bolt including a lever having a projection engage- 120
- able with the extension, a second lever having a projection, remote control mechanism for actuating one of said levers, a handle for actuating the second mentioned lever, and means operable by the remote control mechanism for dogging the handle including a pawl having a portion engageable with the second lever and having a flange engageable by the bolt extension when the bolt is moved in one direction to cause the portion aforesaid to be disengaged from said second lever. 125
9. In a door latch, a case plate, a cover plate on the case plate, a bushing journaled in said plates and having a longitudinally extending recess opening outwardly through one end thereof, a latch bolt journaled on the bushing, and actuating means for the latch bolt including an operating handle having a spindle fitting in the recess aforesaid. 130
10. In a door latch, a case plate, a cover plate on the case plate in substantially parallel relation thereto, a bushing extending through said plates, closed at one end and having a polygonal socket opening outwardly through the other end thereof, a latch bolt mounted on the bushing, and actuating means for the latch bolt including a handle spindle fitting in the polygonal recess. 135
11. In a latch, a case plate, a cover plate carried by the case plate, a bushing extending through said plates, a latch bolt carried by the bushing, and two levers associated with the bushing, one being journaled on the bushing and having a projection engageable with part of the bolt to move the latter from its latching to its releasing position, and the other of said levers being fixed upon the bushing and having a projection engageable with a part of the lever aforesaid to cause the bolt to move from its latching to its releasing position. 140
12. In a latch, a case plate, a cover plate on the case plate, a bushing extending through said plates, a latch bolt carried by the bushing, a lever journaled on the bushing and having a projection engageable with a part of the bolt to move the same, a second lever upon the bushing and having a projection engageable with the lever aforesaid to cause the bolt to move, and a bolt pivoted on one of the plates aforesaid, having a shoulder engageable with one of the levers to render the other inoperative and having a part engageable by a part of the bolt when the latter is moved to cause the lever rendered inoperative to be rendered operative. 145
13. In a door latch, a latch bolt, inside actuating means for the bolt including a remote control link, a member projecting laterally from the link, and a pivoted element movable by said member, outside actuating means for the bolt including a pivotally mounted element, means for dogging the outside means including a member operable by the laterally projecting member upon movement of the 150

link, and means carried by the dogging member and operable by a part of the bolt upon movement thereof incident to closing the door for rendering the dogging member inoperative.

14. In a door latch, a latch bolt, inside actuating means for the bolt, outside actuating means for the bolt, means operable by the inside means for dogging the outside means, and means carried by the dogging means and operable by a part of the bolt upon movement thereof incident to closing the door for rendering the dogging means inoperative.

15. In a door latch, a latch bolt having an extension, inside actuating means for the bolt including a reciprocating remote control link, a lever having a part engageable with the extension, and a pin carried by the link and engaging the lever, outside actuating means for the bolt including a lever having a part engageable with the first mentioned lever, and means rendered effective or ineffective by the pin of the inside actuating means to dog the lever of the outside actuating means.

25 16. In a door latch, a latch bolt having an extension, inside actuating means for the bolt including a reciprocating remote control link, a lever having a part engageable with the extension, and a pin carried by the link and engaging the lever, outside actuating means for the bolt including a lever having a part engageable with the first mentioned lever, and a member operable by the pin of the inside means for dogging the lever of the outside means and rendered inoperative by the extension of the bolt upon movement of the latter incident to closing the door.

40 17. In a door latch, a latch bolt, inside actuating means for the bolt including a reciprocating remote control link, a member projecting laterally from the link, and a pivoted element movable by said laterally projecting member, outside actuating means for the bolt including a pivotally mounted element, and means for dogging the outside means including a pivotally mounted member actuatable by the pin.

50 18. In a door latch, a latch bolt, inside actuating means for the bolt including a reciprocating remote control link, a member projecting laterally from the link, and a pivoted element movable by said laterally projecting member, outside actuating means for the bolt including a member operable by the pin and rendered inoperative by a part of said bolt upon movement thereof incident to closing the door.

In testimony whereof I affix my signature.
EVERETT J. COOK.
